US0D1033048S

(12) **United States Design Patent** (10) **Patent No.:** **US D1,033,048 S**
(45) **Date of Patent:** **** Jul. 2, 2024**

(54) **LOADER HOLSTER**

(71) Applicant: **Wei Yi**, Shenzhen (CN)

(72) Inventor: **Wei Yi**, Shenzhen (CN)

(**) Term: **15 Years**

(21) Appl. No.: **29/780,060**

(22) Filed: **Apr. 22, 2021**

(51) **LOC (14) Cl.** **03-01**

(52) **U.S. Cl.**

USPC **D3/222**

(58) **Field of Classification Search**

(57) **CLAIM**

The ornamental design for a loader holster, as shown and described.

DESCRIPTION

FIG. 1 is a perspective view of a loader holster showing my new design;

FIG. 2 is a top view thereof;

FIG. 3 is a bottom view thereof;

FIG. 4 is a left side view thereof;

FIG. 5 is a right side view thereof;

FIG. 6 is a rear view thereof; and,

FIG. 7 is a front view thereof.

The broken lines depict portions of the loader holster that forms no part of the claimed design.
